UNITED STATES PATENT OFFICE.

JOHANNES U. ROSENHOLM, OF NEW YORK, N. Y.

COMBINATION-TOOL.

1,324,411.

Specification of Letters Patent.

Patented Dec. 9, 1919.

Application filed May 26, 1919. Serial No. 299,958.

To all whom it may concern:

Be it known that I, JOHANNES U. ROSENHOLM, a citizen of Finland, and residing at New York, in the county of Bronx, and 5 State of New York, have invented certain new and useful Improvements in Combination-Tools, of which the following is a specification, such as will enable those skilled in the art to which it appertains to make and 10 use the same.

The object of this invention is to provide an improved tool of the class specified which will serve as a square, as an ordinary rule, as a plumb device, as a level device and as 15 a bevel or miter gage device; and with this and other objects in view the invention consists in a tool of the class specified, constructed as hereinafter described and claimed.

The invention is fully disclosed in the following specification, of which the accompanying drawing forms a part, in which the separate parts of my improvement are designated by suitable reference characters in each of the views, and in which:—

25 Figure 1 is a side view of my improved combination tool and showing the parts in position for use as a square;

Fig. 2 a partial section on the line 2—2 of Fig. 1 and on an enlarged scale;

30 Fig. 3 a partial section on the line 3—3 of Fig. 2 and on an enlarged scale; and

Fig. 4 an end view of the tool looking in the direction of the arrow 4, of Fig. 1.

In the practice of my invention, I provide 35 an elongated body portion *a* which may be of any desired length, and which is of I-beam form and comprises a central web portion *a*² having side members *a*³.

The body portion is saw cut longitudinally at one end thereof to form a longitudinal slot *a*⁴, which communicates at one end with a rectangular recess *a*⁵, which is similarly formed, and the slot *a*⁴ extends longitudinally of the body portion over half of 45 the length thereof, and this makes the parts *a*⁶ of the body portion formed by the slot *a*⁴ slightly elastic.

I also provide an ordinary rule *b* having an approximately rectangular head *b*² which 50 is pivoted in the recess *a*⁵ by means of a bolt *c* provided at one end with a thumb nut *c*² and the rule *b* is adapted to be turned at right angles to the body of the tool as shown in Figs. 1 and 2, or to be folded into the slot *a*⁴ as indicated in dotted lines in Fig. 3.

The head *b*² of the rule *b* is provided with a projecting nose *b*³ and formed on the web portion of the body of the tool at one side thereof, and adjacent to the pivoted head of the rule *b* is a longitudinal shoulder *a*⁷ 60 between which and the adjacent side *a*⁸ of the body portion of the tool is pivoted a lever *d*, the end of which adjacent to the head *b*² of the rule *b* is provided with a nose *d*² adapted to be passed through an aperture 65 *a*⁸ in the web portion *a*² of the body of the tool.

One side of the central web portion of the body of the tool is cut out to form a longitudinal aperture *a*⁹ in said web portion in 70 which the lever *d* is pivoted and in which it operates, and the inner end of said lever is provided with a knob or head *d*³ and pressure applied to the outer end of said lever will force it into the position shown in Fig. 75 2 in which the rule *b* is locked in its operative position, or that shown in Figs. 1 and 2, while pressure on the knob *d*³ will force said lever, or the operative end thereof, outwardly and allow the rule *b* to be folded into the body portion of the tool as indicated in dotted lines in Fig. 3.

Formed in the central part of the web portion of the body of the tool is a longitudinal aperture *e* on the opposite sides of 80 which are placed spirit level tubes *e*² and formed in the web portion of the body of the tool at the opposite ends of the aperture *e* are rectangular apertures *f*, and in the aperture *f* farthest from the pivoted end of 90 the rule *b* is secured a spring pawl *g* having a nose piece *g*² adapted to engage or enter a recess *b*⁴ in the free end of the rule *b*, as indicated in Figs. 1 and 3, and this pawl serves to hold the rule in its closed position 95 and may be moved through the aperture *f* in which it is secured to release said rule, but the operation of said pawl in engaging the end of said rule when the latter is forced into its closed position is automatic. 100

The apertures *f* also serve as aids in placing the spirit level tubes *e*² in position, and in securing them in position, and by passing a finger through either of said apertures, the rule *b* may be forced out of its closed position so that it can be engaged by the hand or fingers of the operator. 105

In the end portion of the body of the tool opposite the pivoted rule *b* is another transverse aperture *h* in which are placed and se. 110

cured to the transverse spirit level tubes *i*, and the operation of the device will be readily understood from the foregoing description when taken in connection with the 5 accompanying drawing and the following statement thereof.

The spirit level tubes *e*² arranged longitudinally of the tool, or the body portion thereof, enable the device to be used as a 10 spirit level with either side up, and the spirit level tubes *i* arranged transversely of the tool, or the body portion thereof, enable the device to be used as a plumb with either end up; and by reason of the connection of the rule *b* with the body portion said rule may be turned at right angles to 15 said body portion as shown in Figs. 1 and 2 where it may be locked by the lever *d*, or it may be turned at any angle from zero 20 to 90° and locked in such position by the bolt *c* and thumb nut *c*², and this enables the device to be used as a miter or bevel gage, and by means of the construction shown and described, I provide a tool of the class specified 25 which is simple in construction and operation and which may be easily and conveniently used for all the purpose specified, and which will not easily get out of order, or be broken or otherwise injured; and while 30 I have shown details of construction which I prefer in carrying my invention into effect, it will be understood that the said invention is not limited to the exact details of construction herein shown and described, and 35 changes therein and modifications thereof may be made, within the scope of the appended claims, without departing from the spirit of my invention or sacrificing its advantages.

40 Having fully described my invention, what I claim as new and desire to secure by Letters Patent, is:—

1. A tool of the class described comprising an oblong body portion provided centrally thereof with an oblong aperture in 45 which is secured two spirit level tubes and in one edge portion thereof with a transverse aperture in which is secured two spirit

level tubes, said body portion being also provided with a rule which is pivoted in one 50 end portion thereof, and in one side edge portion thereof with a longitudinal slot into which said rule is adapted to fold, means for locking said rule in its extended position, and means for locking said rule in its closed 55 position.

2. A tool of the class described comprising a body portion composed of separate parts, said body portion being provided in one end thereof with a rectangular recess 60 and in the other end portion thereof with a transverse aperture and in one side edge portion thereof with a longitudinal slot which communicates with said recess and with said aperture, a rule having a head 65 pivoted in said rectangular recess and adapted to fold into said slot and into said aperture, and a lock device in said aperture for securing said rule in its closed position.

3. A tool of the class described comprising a body provided in one end thereof with a rectangular recess and in the opposite end portion with a transverse aperture, said body being also provided in one side edge portion thereof with a longitudinal slot 75 which communicates with said recess and with said aperture, a rule having an approximately rectangular head which is pivoted in said recess, said rule being adapted to fold into said slot and into said aperture, the head of the rule being provided with a 80 projecting nose and a lever pivoted in the body and adapted to operate in connection with said nose to lock said rule in an open position, said aperture being also provided with a lock device for securing said rule in a closed position.

In testimony that I claim the foregoing as my invention I have signed my name, in presence of the subscribing witnesses, this 90 24th day of May, 1919.

JOHANNES U. ROSENHOLM.
